Attorney:

UNITED STATES PATENT OFFICE.

CHARLES R. TEATS, OF COLUMBUS, OHIO.

DESIGN FOR A GAME.

55,401.

Specification for Design.

Patented June 1, 1920.

Application filed November 5, 1918. Serial No. 261,304. Term of patent 14 years.

To all whom it may concern:

Be it known that I, CHARLES R. TEATS, a citizen of the United States, residing at Columbus, in the county of Franklin and State of Ohio, have invented a new, original, and ornamental Design for Games, of which the following is a specification, reference being had to the accompanying drawing, forming part hereof.

The figure is a perspective view of a game, showing my new design.

I claim:

The ornamental design for a game, as shown.

CHARLES R. TEATS.
